ELECTRICIAN'S TOOL

William Wollenweber, Sacramento, Calif.

Application January 8, 1937, Serial No. 119,659

1 Claim. (Cl. 81—9.5)

This invention relates generally to an electrician's tool and in particular relates to, and it is my principal object to provide, an electrician's tool designed to facilitate the removal of the covering and insulation from electric wire at those points on the wire where connection with other wires is to be made.

Heretofore, electricians have usually used a common "jack" knife or other hand knife to remove the covering and insulation. Not only was this a rather difficult and clumsy operation, but it required too long to prepare and make the connections between separate wires. To overcome these objections to the use of a common knife, I have produced the herein described tool.

A further object of my invention is to provide an electrician's tool which may be effectively used to twist one wire about another and to make a tight connection and positive contact between the wires. The tool is also provided with wire stripping and cutting means.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

30 In the drawing similar characters of reference indicate corresponding parts in the several views:

Fig. 1 is a side elevation of the tool with the tool bar raised from the case.

35 Fig. 2 is an end view of the tool.

Fig. 3 is a fragmentary sectional elevation taken on line 3—3 of Fig. 2.

Fig. 4 is a transverse section taken on line 4—4 of Fig. 1.

40 Fig. 5 is a transverse section taken on line 5—5 of Fig. 1.

Fig. 6 is a transverse section taken on line 6—6 of Fig. 1.

45 Referring now more particularly to the characters of reference on the drawing, my improved tool comprises a case or frame 1, similar in construction to the case of an ordinary "jack" knife. A tool bar 2 is pivoted, as at 3, within the case at one end thereof for swinging movement in and out of the case. A snap spring of the character commonly used in folding knives is employed in connection with the tool bar 2 and is disposed in the bottom of the case.

50 The tool bar is formed at its outer or free end with a head, indicated generally at 4, of

a width substantially the distance between the sides 5 of the case. Rearward of the head, the case is separated by a partition 6, the tool bar there being of such width as to normally rest between the partition and one wall 5 of the case. If desired, a short screw driver 7 may be mounted on and project from the back end of the case. Also if desired, another implement such as a knife blade may be mounted in the case to one side of the tool bar or on the opposite side of partition 6. A ring 8 on the outer end of the tool bar serves as a means for easy withdrawal of the tool bar from the case.

10 The head 4 is formed with a passage 10 extending from its inner to the outer edge, said passage being tapered as shown. The sides of the head intermediate the ends of the passage and at the inner edge of the bar are notched as at 11, the edges of the notches being sharp. The notched portion has another inward and 15 smaller notch 12 for the purpose hereinafter described.

15 A cutting blade 13, preferably hollow ground, is secured on the lower edge of the tool bar, 20 by a bolt 13, the cutting edge projecting between the sides of the head and into the passage to a termination close to the notch 12 and just inwardly of the bottom of the sharp notches 11. The blade is slotted, as at 15, and thus 25 is adjustable. Both sides 5 of the case are notched, as at 16, to form a cradle for the purpose hereinafter described, said cradle being so disposed as to match notches 11 when the tool bar is in lowered position. A bumper or 30 stop 17, preferably of rubber, is disposed in the case at the forward end and serves to limit downward movement of the tool bar, the head 4 striking said bumper with the downward or 35 closing movement of the bar.

The forward end of the case is formed with 40 two longitudinally extending holes 18, one being of a greater diameter than the other. A transversely extending, substantially semi-circular groove 19 is formed in the case end immediately 45 below said holes.

Intermediate the ends of the case, the sides 5 are drilled with transversely aligned holes 20, while the tool bar is notched, as at 21, the notched portion being sharpened on one side to a cutting edge 22 and which edge, when the tool bar is in closed 50 position, terminates in a plane a short distance above the center of holes 20, as clearly shown in Fig. 5.

Adjacent the rear or pivot end of the case, the upper edge of sides 5 are notched as at 23, one 55

inside edge 24 being sharpened. The tool bar is formed with a corresponding notch 25 having a sharpened and cooperating cutting edge 26.

Use

5 In use, my improved tool is employed as follows:

To expose a portion of the wire in a length of insulated wire, in order to make a tapped connection, the tool bar is raised approximately 45° and the wire disposed in the cradle formed by notches 16. The tool bar is then lowered or snapped down until notches 11 engage the wire. (See Figs. 3 and 6.) The entire tool is then 10 rotated about the wire 3 or 4 times in a clockwise direction. With such operation, the notches 11 first score the insulation and covering, and then 15 the blade 13 cuts away the covering and insulation and the uncovered portion of the wire then 20 engages in small notch 12 and thus cannot be nicked or cut. The covering and insulation cut away as shavings, escapes through tapered opening 10. If desired, dual blades (one on each side 25 of the opening) may be used rather than a single blade as shown.

To connect another wire A to such exposed portion of wire B, the bare end of the other wire is placed in one of holes 18 (whichever is the correct diameter) and the wire B placed in groove 30 19 and the tool passed about wire B causing wire A to be wound tightly about wire B. The initial position of such wires is shown in dotted lines in Fig. 3.

To strip the covering from the end of a wire, 35 the wire is placed through holes 20, the tool bar lowered, and the tool then rotated about the wire, illustrated in Fig. 5 as C. Cutting edge 22 cuts through the covering and insulation but does not cut the wire due to its configuration and 40 termination short of the center of holes 20. When

so cut, the covering and insulation may be easily stripped from the wire beyond the lines of cut.

To cut a wire, it is placed across the case transversely in notches 25 and the tool bar lowered, causing cooperating cutting edges 24 and 26 to 5 shear the wire with a clean cut.

If desired, cutting edges 22 or 26 may be used as a scraper blade to clean tarnished wire, etc.

From the foregoing description it will be readily 10 seen that I have produced such a device as substantially fulfills the objects of the invention as set forth herein.

While this specification sets forth in detail the present and preferred construction of the device, still in practice such deviations from such detail 15 may be resorted to as do not form a departure from the spirit of the invention, as defined by the appended claim.

Having thus described my invention, what I claim as new and useful and desire to secure by 20 Letters Patent is:

An electrician's tool comprising a case having spaced sides, a tool bar pivoted in the case at one end for movement in and out of the same, the upper edges of the case adjacent the opposite end 25 having matching notches forming a cradle for the reception of a covered and insulated wire, a cutting head mounted on the outer end of the bar, said head having a passage therethrough from the edge adjacent the cradle to the opposite edge, 30 the sides of the head being notched to engage over a wire on the cradle, a cutting blade, and means mounting said blade on the head with the cutting edge thereof in position between said sides of the head and adjacent the passage, 35 whereby with relative rotation between the tool and wire on the cradle and engaged by the head, the cutting blade will cut away the covering and insulation of the adjacent portion of wire.

WILLIAM WOLLENWEBER. 40
